CLAIM

The ornamental design for a clock body, as shown.

DESCRIPTION

This application relates to the ornamental design of a clock body illustrated in the accompanying drawings, in which:

FIG. 1 is a right rear perspective view of a clock body showing my new design;
FIG. 2 is a front elevational view thereof;
FIG. 3 is a right side elevational view thereof; and
FIG. 4 is a right front perspective view thereof.

FIG. 1

FIG. 2

FIG. 3

FIG. 4
